UNITED STATES PATENT OFFICE

164,092

DOLLY

Leon H. Best, Galva, Ill., assignor to John H. Best & Sons, Inc., Galva, Ill., a corporation of Illinois

Application October 12, 1950, Serial No. 12,536

Term of patent 14 years

(Cl. D14—3)

To all whom it may concern:

Be it known that I, Leon H. Best, a citizen of the United States, residing at Galva, in the county of Henry and State of Illinois, have invented a new, original, and ornamental Design for a Dolly, of which the following is a specification, reference being made to the accompanying drawing forming a part hereof.

In the drawings:

Figs. 1, 2 and 3 are perspective views of a dolly embodying my novel design; and

Fig. 4 is a perspective view similar to Fig. 1 but showing the handle of the dolly in its extended position.

I claim:

The ornamental design for a dolly, substantially as shown.

LEON H. BEST.
